UNITED STATES PATENT OFFICE.

OSCAR A. NORRING, OF NEW YORK, N. Y.

WINDOW-LOCK.

1,209,481.

Specification of Letters Patent. Patented Dec. 19, 1916.

Application filed September 11, 1915. Serial No. 50,226.

To all whom it may concern:

Be it known that I, OSCAR A. NORRING, a subject of the Czar of Russia, residing at New York, in the county of New York and 5 State of New York, have invented certain new and useful Improvements in Window-Locks; and I do hereby declare the following to be a full, clear, and exact description of the invention, such as will enable others 10 skilled in the art to which it appertains to make and use the same.

This invention relates to new and useful improvements in window locks and the principal object of the invention is to provide 15 a device which is capable of being readily applied to windows of the ordinary type without changing the construction thereof.

Another object of the invention is to provide 20 a lock which will hold the windows in various adjusted positions and which will also hold the upper and lower sashes against independent relative movement.

A further object of the invention is to provide 25 a device which will effectively lock the windows open so as to allow for ventilation and still prevent the same from being opened wider.

A further and more specific object of the invention is to provide a lock capable of 30 locking the upper and lower sashes as well as the entire window in any position.

With these and other objects in view, the invention consists in the novel combination 35 and arrangement of parts which will be fully set forth in the following specification and accompanying drawings, in which:—

Figure 1 is a fragmentary view of a window 40 partially in section, illustrating this improved lock applied thereto. Fig. 2 is a sectional view on line 2—2 of Fig. 1. Fig. 3 is a perspective view of the keeper bar, and Fig. 4 is a view illustrating the key.

Referring now to the drawings by characters of reference, the numeral 1 designates the central or upper bar of the lower sash, while the numeral 2 designates the side bar of the upper sash. Secured to the side bar 45 2 is the keeper plate or bar 3, which is best illustrated in Fig. 3 and comprises the elongated rectangular body 4 provided at each end with the angular extensions 5 and the ears 6, which are formed with screw receiving openings 7, by which the device is attached to the sash or frame of the window.

A plurality of spaced apertures 8 are formed at intervals in the body 4 and through these apertures extends a locking pin, which will be more fully hereinafter 60 described. It is to be understood that the same construction of bar is used on the stop 9 of the window casing as indicated.

The lock structure, which is carried by the upper or mid-rail 1 of the lower sash, 65 is generically indicated by the numeral 10 and it includes a housing 11, which is attached to the upper rail 1 in any suitable manner. The housing 10 is provided with openings 12 and 13 formed in its walls, 70 which openings are disposed at right angles to each other. The opening 12 faces the side rail 2 of the upper sash and the opening 13 faces the stop 9 of the window frame. Ears 14 and 15 are formed upon the walls 75 16 and 17 of the casing 11, and they are provided with openings 18, extending therethrough. Locking bolts 19 and 20 are slidably carried by the ears 14 and 15 respectively. The locking bolt 19, which has its 80 locking end 21 projecting outwardly through the opening 12, is also slidably mounted within a guide-way 22 formed within the housing 11 and extending inwardly from the opening 12. An ear 23 is formed upon 85 the wall 16, and extends inwardly parallel to the ear 14. A spiral spring 24 is coiled about the locking bolt 19 and one end of the spring engages a collar 24^a which is mounted upon the bolt 19 and abuts the 90 inner end of the sleeve 22, while the other end engages the ear 23, tending to force the locking bolt 19 outwardly at all times.

The reduced end 25 of the locking bolt 19 is slidably carried by the plate or ear 14, 95 and it has a head 26 formed upon its terminal, which is provided for limiting the forward sliding movement of the bolt 19. The bolt 19 further has a projection 27 formed thereon. The projection 27 is provided for 100 being engaged by the key indicated at 28, which is inserted through a key hole 29 formed in the outer surface 30 of the housing or casing 11, for forcing the locking bolt inwardly out of a locking position, and moving its outer locking end 21, out of one of the recesses 8, which is formed in the keeper 3.

The locking bolt 20 is identical in construction to the locking bolt 19, and it has 110 a projection 32 formed thereon, which is adapted for engagement by the key 28 for

moving the locking bolts 20 out of a locking position with respect to the keeper 3, which is carried by the stop 9 of the window frame.

5 The cover 30 of the housing or casing 11, is removably mounted upon the casing and is held in place, by means of screws or analogous devices indicated at 33.

From the foregoing description taken in
10 connection with the accompanying drawings
the advantages of construction and of the
method of operation of the improved win-
dow lock will be readily apparent to those
skilled in the art to which this invention ap-
15 pertains and, while in the foregoing descrip-
tion, the principle of the operation of this
invention has been described together with
various features of construction, it is to be
understood that certain minor features of
20 construction, combination and arrangement
of parts may be altered to suit practical
conditions provided such alterations are
comprehended within the scope of what is
claimed.

25 What is claimed is:—

In a window lock structure, the combi-
nation with a window structure including up-
per and lower sashes, and a frame carried
stop, of a keeper carried by one of the side
30 rails of said upper sash, said keeper being
provided with a plurality of spaced locking

bolt receiving openings, a second keeper car-
ried by said stop, said second named keeper
being provided with a plurality of locking
bolt receiving openings, a locking structure 35
carried by the upper rail of said lower
sash, said locking structure including a
housing, a plurality of ears extending in-
wardly from the walls of said housing,
sleeves formed upon and extending inwardly 40
from the walls of said housing, locking bolts
slidably carried by said ears and said sleeves
and positioned substantially at right angles
with respect to each other, spiral springs
coiled about said locking bolts for normally 45
holding them in a locking position, projec-
tions formed upon said locking bolts and
adapted for engagement with a key for mov-
ing said locking bolts into an unlocking po-
sition against the tension of said springs, 50
heads formed upon the inner ends of said
locking bolts and adapted for engagement
with certain of said ears for limiting the out-
ward movement of said bolts, and collars
mounted upon said bolts and engaging the 55
inner ends of said sleeves.

In testimony whereof I affix my signature
in presence of two witnesses.

OSCAR A. NORRING.
